UNITED STATES PATENT OFFICE.

HORACE HURM, OF PARIS, FRANCE.

STYLUS SUPPORT FOR TALKING MACHINES.

Application filed August 9, 1921. Serial No. 490,998.

To all whom it may concern:

Be it known that I, HORACE HURM, citizen of the French Republic, residing at Paris, France, have invented certain new and useful Improvements in Stylus Supports for Talking Machines, of which the following is a specification, the present application being drawn to cover subject matter divided out of my copending application 10 Serial No. 377,992, filed April 30, 1920.

The subject of the invention is a stylus support for talking machines, the principal characteristic of which is that it is formed as a sort of lattice construction extending 15 over the whole length of the support. This renders it possible for the stylus support to be small in inertia yet sufficiently rigid to resist bending. Known stylus supports usually are defective in that they are not sufficiently rigid, and thus easily become distorted, so that the delicate vibrations of the stylus are not transmitted to the diaphragm of the sound box with sufficient accuracy. The stylus support of the invention is particularly intended for a sound box in which the stylus support is not rigidly connected 20 with the diaphragm, but, in known manner, rests thereupon unconnected and transmits by reason of its constant contact, the movement of the stylus to the diaphragm. In such case, it is necessary that the diaphragm be preliminarily bent from its central position for a certain degree by the stylus support, so that a certain tension exists between 25 these two parts. This tension causes the two parts to remain in contact, no matter to which side the vibration takes place. In accordance with the invention, this tension is calculated of such size that the curve produced is at least equal to half of the largest 30 width of vibration which takes place. With an unconnected stylus support, so large a tension assures an absolutely correct transmission of movement and therewith a true 35 reproduction of the sounds of tones. Such an arrangement fulfills all requirements as to the rigidity of the stylus support, which is due to its formation similar to a truss or lattice support. In addition, the height of 40 the lattice construction renders it possible in simple manner to provide as it will be shown hereafter a suitable point of engagement for the spring, or the like, producing the tension.

50 The drawing illustrates the subject of the invention in two forms of construction.

Figs. 1 and 2 show a sound box with the stylus support of the invention in elevation and cross section. Figs. 3 and 4 are corresponding illustrations of the other modification, which differs slightly with respect to the form and engagement of the spring.

In the drawings:—

The diaphragm *a* which, according to Fig. 4 has a flat rigid center or according to Fig. 2 is shown arched or curved, is arranged in known manner in the housing *b* of the sound box and may be inserted therein by means of a ring *c* of resilient material. The end of the stylus support or bar *d*, which in the present case, is formed like a lattice support, lies at the center of the diaphragm under a certain constant pressure. It consists suitably of a material which is of low density, such as, duralumin, magnalium, fibre or the like. By the latticed construction over the entire length of the stylus bar I obtain a great rigidity and lightness, while at the same time preventing flexibility and excessive inertia which would be the causes 80 of an incorrect transmission of the recorded sound waves.

The part of the support, which serves for the reception of the stylus *a*, is provided with a perforation extending clear through, so that it is possible to use a stylus of great length and to attach it in such manner that it may extend from the support and respond to the requirements under which it must operate. The other end *d*¹ of the stylus support may be provided with a simple point, by means of which the support may be positioned, unconnected, but with a certain degree of pressure, on the diaphragm. This pressure is so calculated that the deformation caused thereby in the position of rest of the diaphragm is greater than the amount in which it will vibrate in one or the other direction, from its position of rest, in the operative position.

The lattice support is mounted with its edge facing the sound box in known manner by means of adjustable knife edges, or points. In the present case two small pointed screws *f* are arranged in projections *g* of the sound box, the points of which engage in suitable depressions of a transverse element *h* provided on the support. To this transverse element is attached the end *d*² of the support carrying the stylus, so that the other end *d*¹ is adjacent the center of the diaphragm *a*. The spring lying substantially

parallel to the diaphragm holds the stylus support to the sound box *b*, has a double action pressing it on the one end against the adjustable point screw *f*, and on the other hand, by means of the above mentioned tension, pressing it against the diaphragm. For this double purpose use is made of a hook *d*³ which is constructed at a point lying outside of the connecting line of the point of mounting, this hook being simply formed by a cavity or depression. The height of the special stylus-holder affords a special advantage when compared to the usual rod-like stylus-holders as it dispenses with the necessity of providing a special projection for the purpose of having the hood *d*³ placed at a proper distance from the plane of the fulcrum points *f*. The said hook engages the end of a spring which, at the same time exerts a pressure against the point screw *f*, as well as a rotary movement on the lattice support. The spring may be a spiral spring which is provided at one end with a loop of wire or cord, or the like, by means of which it is hooked to the lattice support. Thus it can be easily unhooked, and the stylus support and the membrane directly removed, if necessary. The other end of the spring which, at *k*, is suitably stretched at the center, with respect to the two projections, thus remains permanently connected with the housing. The spring arrangement, not only permits of the convenient removal of the stylus support and the membrane, but also permits of any desired pressure adjustment at the point *d*⁴ so that it is always possible to adjust said point on the stylus support accurately on the diaphragm to obtain the best effects. The clearness and purity of the reproductions can be controlled in simple manner at any time.

Having described my invention what I claim as new and desire to secure by Letters Patent, is:—

1. In combination a diaphragm, a stylus support arranged in front of said diaphragm, said stylus support comprising a flat member presenting its edge toward said diaphragm, said flat member being relatively narrow at the top and wide at the bottom, a projecting element at the top of said stylus support engaging said diaphragm, and a spring secured to said stylus support at the bottom for tensioning said projecting element against said diaphragm, the force of said spring being directed in a line almost perpendicular to the direction of oscillation of said stylus support when vibrating, so that the movements of said stylus support are resisted by a small component only of the entire force of said spring.

2. In combination, a sound box, a diaphragm supported in said sound box, said

sound box being provided with a fulcruming element, a stylus support comprising a flat member presenting an edge toward said diaphragm and having a transverse base engaging said fulcruming element, said flat member being narrow at the top and wide at the bottom, a point projecting from the top into contact with the diaphragm, a spring secured at one end to the bottom of said flat member beyond the fulcruming element and secured at its other end to the sound box for maintaining said point in pressure engagement with said diaphragm.

3. A sound box adapted for use with talking machines, said sound box having a central bore, a diaphragm stretched across said bore, a stylus support consisting of a flat member triangular in shape and having a transverse element provided with depressions on its upper face, pivot members on said sound box adapted to rest in said depressions, the upper end of the triangular support resting against the diaphragm, a tensioning spring connected to said sound box at one end and looped over the end of said triangular member for holding the pivot members in said depressions and the end of the support against said diaphragm.

4. A sound box adapted for use with talking machines, said sound box having a central bore, a diaphragm stretched across the end of the bore, pivot members extending downwardly from said sound box, a triangular stylus support having transverse members extending from either side thereof, depressions in upper side of said transverse member adapted to receive the ends of said pivot members, stylus support carrying a stylus, carrying at one corner a stylus, another corner resting against the diaphragm of the sound box and the other provided with a hook member, a tension spring secured to said sound box and provided with a loop adapted to rest in said hook member for holding the stylus support in contact with said diaphragm and the transverse element in contact with said pivot members.

5. In combination, a sound box, a diaphragm mounted in said sound box, a stylus bar pivoted near one end to said sound box and having its other end in contact with said diaphragm, said stylus bar having a spring connected to a stationary point above the diaphragm and to the stylus bar at a point offset from the pivot.

In testimony whereof I have hereunto set my hand in presence of two subscribing witnesses.

HORACE HURM.
